United States Patent Office

Des. 194,784
Patented Mar. 12, 1963

194,784

ANIMAL FEEDING TUB

Noble Van Voorhis, Los Angeles, Calif., assignor to Carnation Company, Los Angeles, Calif., a corporation of Delaware

Filed Feb. 12, 1962, Ser. No. 68,769

Term of patent 14 years

(Cl. D12—2)

FIG. 1.

FIG. 2.

FIG. 3.

FIG. 4.

FIG. 1 is a perspective view of the animal feeding tub on a reduced scale, showing my new design.

FIG. 2 is a top plan view thereof.

FIG. 3 is a side elevational view thereof.

FIG. 4 is a bottom view thereof.

I claim:

The ornamental design for an animal feeding tub, as shown.
